(57) **CLAIM**

I claim the ornamental design for a breast nodule stabilization device, as shown and described.

DESCRIPTION

FIG. 1 is a perspective view of a breast nodule stabilization device, showing my new design;

FIG. 2 is a front elevational view thereof;

FIG. 3 is a rear elevational view thereof;

FIG. 4 is a right-side elevational view thereof, the left-side elevational view being a mirror image thereof; and,

FIG. 5 is a top plan view thereof, the bottom plan view being a mirror image thereof.

The broken lines showing a woman in FIG. 1 are included for the purpose of illustrating the invention in use, and form no part of the claimed design.
